UNITED STATES PATENT OFFICE.

MATTHIAS BROCK, OF BOSTON, MASSACHUSETTS, ASSIGNOR TO UNITED SHOE MANUFACTURING COMPANY, OF PATERSON, NEW JERSEY, A CORPORATION OF NEW JERSEY.

LASTING-MACHINE.

1,188,620.

Specification of Letters Patent. Patented June 27, 1916.

Application filed June 15, 1915. Serial No. 34,248.

To all whom it may concern:

Be it known that I, MATTHIAS BROCK, a citizen of the United States, residing at Boston, in the county of Suffolk and State 5 of Massachusetts, have invented certain Improvements in Lasting-Machines, of which the following description, in connection with the accompanying drawings, is a specification, like reference characters on the 10 drawings indicating like parts in the several figures.

This invention relates to lasting machines of the "bed" type, and particularly to end lasting mechanism of such machines and has 15 for its object to secure more effective lasting or conformation of the upper materials to the contour of the end portion of the last. In this type of lasting machine, a pair of comparatively thin wiper plates are butted 20 together to present an acting edge shaped to fit the end portion of a last. For toe lasting the wipers and the last are usually moved relatively to wipe the upper up the side face of the last in order that it shall 25 be properly stretched about the last without wrinkles and then the wipers are advanced and closed over the last bottom to lay the margin of the upper over the feather and against the channel lip or rib of the inner- 30 sole where it is secured in lasted position. It is found that the wipers lose more or less of their frictional hold on the upper during the change of direction of their movement between the end of the upward wipe and 35 the inward wipe and that consequently the upper has a tendency to slip back from under the wipers after they have tensioned the upper about the last.

An important object of the present in- 40 vention, therefore, is to conform the upper of the shoe to the last and to the innersole with such degree of accuracy as to enable subsequent operations to be performed to the best advantage for the desired appear- 45 ance of the shoe.

In accordance with an important feature of the invention, novel means are provided to coöperate with the wipers in wiping or rubbing the upper up the side faces of the 50 last and to hold it under tension during the overlaying action of the wipers. The means herein shown as embodying this feature of the invention is also adapted to assist the end embracing wipers in molding the

upper into conformation with the end por- 55 tion of the last and innersole at either end of a shoe. For these purposes said means, as shown, consists in metallic end embracing plates having a similar edge contour to that of the end embracing wipers and connected 60 thereto for movement relatively to the wipers in paths which maintain the edges of the plates substantially parallel with the acting edges of the wipers. Preferably the plates present a vertically extended acting face of 65 substantially greater height than it is practical to provide on the edge of the end embracing wipers.

In accordance with a further feature of this invention, the wipers and the end embrac- 70 ing plates are preferably heated, thereby increasing the effectiveness of their action upon the material and also causing the upper to be shaped and "set" with a sufficient degree of permanence to prevent the upper 75 from readily losing the form of the last after the lasting operation. The relatively wide acting faces of the heated end embrac- 80 ing plates enables said plates, as they press or rub against the side faces of the shoe 85 to iron out any wrinkles formed in the upper and to give precision of shape to that portion of the shoe at and adjacent to the edge of the shoe bottom.

These and other features of the invention 85 will appear more fully in the following description when considered in connection with the accompanying drawings of a preferred embodiment of the invention and will then be pointed out in the claims. 90

In the drawings: Figure 1 is a plan view of a toe lasting mechanism embodying this invention; Fig. 2 is an inverted plan view of the wiper mechanism; Fig. 3 is a plan view of the wiper mechanism in operative 95 relation to the toe of a shoe; and Fig. 4 is a section on the line 4—4 of Fig. 3.

The toe lasting apparatus herein illus- 100 trated as one to which the invention is appli- 105 cable is similar to that shown and de- 105 scribed in United States Letters Patent No. 1,018,477 granted on application of Matthias Brock and comprises a toe lasting head 2 mounted for vertical movement in the ma- 110 chine frame by a treadle to produce an up- 115 ward wiping or rubbing action along the side faces of the last to the bottom thereof after the wipers have been partially closed.

to embrace the toe of the shoe. Downward movement of the lasting head is employed for compressing the wiper over upper upon the feather of the innersole after 5 the wipers have been further closed in over the shoe bottom. There are also the usual adjusting devices for accommodating the plane of the wipers to the longitudinal and transverse inclinations of the bottom of the 10 last.

The wipers 6, which have an edge contour shaped to embrace completely the toe portion of a shoe, are plates detachably secured to wiper carriers 8 and 9 interposed between 15 a table formed on the machine frame and a cover plate 14. The wiper carriers are provided with cam slots 16, 16 which receive stationary guide rolls 17 secured between the table and cover plate 14 and 20 are connected by links 18 and a cross head 20 with a plunger 22 extending longitudinally of the machine and operated by a hand lever 24 connected to the plunger at 25 and to the frame at 26. Through these 25 connections the wipers receive a combined advancing and closing movement relatively to the shoe.

In accordance with the illustrated embodiment of this invention coöperating metallic toe embracing plates 28 are secured to the under side of the wipers by a stud and cam slot connection, shown as comprising cam slots 30 in the forward end of each of the wipers 6 and other cam slots 32 in the 30 rear end of each of the toe embracing plates 28 into which project the respective shouldered studs 34. These cam slots 30 and 32 are respectively concentric with the cam slots 16, 16 in the wiper carriers 8 and 9 so 35 that the work engaging faces of the toe embracing plates 28 and the acting edge faces of the wipers 6 are maintained in parallel relation to each other during their relative movements. Comparatively strong spring 40 pressed plungers 36 located in a recess in the forward portion of each of the wiper carriers 8 and 9 engage the heads of the studs 34 mounted on the toe embracing plates and normally maintain the acting edge faces of 45 the toe embracing plates 28, 28 substantially flush with the acting edge faces of the wipers and permit said toe embracing plates to retreat relatively to the wipers and against the resistance of said plungers during 50 the advancing movement of the wipers. The toe embracing plates are never required to close inwardly over the bottom of the shoe and therefore their acting edge faces may advantageously be formed entirely with 55 reference to the side faces of the last, both as to the longitudinal contour around the end of the toe and as to their shape in vertical section. In this latter respect they preferably present a vertically extended work 60 engaging face of substantially greater

height than it is practical to provide on the edge of the toe wipers and form a square corner with the bottom face of the wipers.

A further important function of the toe embracing plates resides in preventing the 70 wipers from advancing over the shoe bottom a sufficient distance to break down or otherwise damage the channel lip or rib on a welt innersole as frequently occurs when lasting a shoe in which the upper materials 75 require the application of more force to wipe them inwardly against the lip at one side or part of the toe than at the other side. The distance the wipers may advance over the shoe bottom is controlled by the cam 80 slots 30 and 32, the length of which determines the amount of relative movement between the wipers and the toe embracing plates, which is preferably equal to the width of the feather of the innersole. 85

Secured to the cover plate 14 is a holder 37 provided with an aperture in which is received an electrical heating unit 38 from which heat is conducted through the cover plate 14 to the wipers and to the toe embracing plates while they are in retracted inoperative position under the cover plate 90 between their operations on successive shoes. The presence of heat in the wipers and in the toe embracing plates increases the effectiveness of their action upon the upper material. 95

In the use of the invention as embodied in the described construction, the toe embracing plates are advanced into position to embrace the toe portion of the shoe simultaneously with the advance of the wipers and the plates coöperate with the wipers in rubbing or wiping the upper up the side faces of the last. By reason of the fact that the toe 100 embracing plates present a substantially wide acting face as compared with the thin acting edges of the wipers and that they are also in heated condition their action on the upper is much more effective than constructions heretofore proposed and enables the upper to be conformed to the last more smoothly and with greater precision. When the wipers have reached a position substantially flush with the surface of the 105 shoe bottom and begin to close the toe embracing plates automatically clamp and hold the tensioned upper against the side faces of the last so that no tension on the upper is lost during the change of direction of the 110 wiper movement and through the yielding connections of the plates 28 with the wipers the holding upper shaping pressure of the plate is increased as the wipers are advanced in a horizontal plane to wipe the upper 115 over the feather and against the channel lip on the innersole. The wipers may be backed away from the lip on the innersole and then advanced repeatedly if necessary 120 while the plates 28 continue to hold the 125 upper. The wipers are held in position by the cam slots 30 and 32 and the cam 130

upper clamped to the side faces of the last so that it cannot slack back.

The heated toe embracing plates together with the wipers provide co-operating metallic surfaces with which the upper about the side faces of the last and on the feather of the innersole can be blocked to produce the sharp angular formation which is desirable at the outer edge of the shoe and the upper 10 along said edge can be set with that degree of permanence required to improve the conditions for subsequent operations on the shoe.

Metallic toe embracing plates having pre-determined edge contours, in which this invention is shown as embodied, are to be clearly distinguished from the pads and flexible bands heretofore proposed which consist of or were faced with leather or other 20 non-rigid material capable of adapting itself to the shape of the portion of the work which it engages rather than imparting a particular shape to the work.

Having described my invention, I claim 25 as new and desire to secure by Letters Patent of the United States:—

1. In a lasting machine, the combination with end embracing wipers and operating means for advancing and closing the wipers 30 to lay an upper over an innersole; of end embracing plates located under said wipers and having a similar edge contour to that of the wipers, and means connecting said plates and said wipers, said connecting 35 means permitting relative movement between the wipers and plates and normally maintaining the acting edge faces of the embracing plates substantially parallel to the acting edge faces of the wipers.

2. In a lasting machine, the combination with end wipers and operating means for advancing and closing the wipers to lay an upper over an innersole; of end embracing plates secured to said wipers, and means 45 guiding and directing relative movement between said wipers and said plates in paths which maintain the edges of the plates substantially parallel with the acting edges of the wipers.

3. In a lasting machine, the combination with end wipers and operating means for advancing and closing the wipers to lay an upper over an innersole; of end embracing plates secured to said wipers and movable 55 relatively thereto, means for directing such movement, and means for yieldingly resisting such relative movement and causing said plates to clamp the upper against the side faces of the last yieldingly while permitting 60 the wipers to be advanced a predetermined distance over the shoe bottom.

4. In a lasting machine, the combination with end wipers and operating means for advancing and closing the wipers to lay an 65 upper over an innersole; of end embracing

plates secured to the under side of said wipers and movable relatively thereto, and means to limit said relative movement and cause the plates to control the distance which the wipers may be advanced over the shoe 70 bottom.

5. In a lasting machine, the combination with end wipers and operating means for advancing and closing the wipers to lay an upper over an innersole; of end embracing plates carried by the wipers and having a relatively wide acting face of a similar contour to that of the wipers, means for yieldingly maintaining the acting edges of the plates normally flush with the acting edges 80 of the wipers, and connections permitting the wipers to advance over the shoe bottom while the plates are clamping the tensioned upper against the sides of the last yieldingly.

6. In a machine of the class described, end lasting mechanism comprising two sets of toe embracing plates mounted and guided for similar advancing and turning movements to embrace a shoe end, a single operating means for said plates, and a connection between said plates for permitting one of said sets of plates to be advanced over the shoe bottom while the other of said sets of plates acts to clamp the upper yieldingly 90 against the last.

7. In a machine of the class described, shoe end shaping mechanism comprising two sets of end embracing plates mounted and guided for similar advancing and turning movements to embrace a shoe end, the mounts for the plates permitting one of said sets of plates to advance and close over the shoe bottom while the other of said sets of plates acts to clamp the upper yieldingly 95 against the last.

8. In a lasting machine, the combination with end wipers and operating means for advancing and closing the wipers to lay an upper over an innersole; of end embracing plates located directly beneath the wipers and having relatively wide acting edges of a contour similar to that of the wipers, a stud and slot connection permitting relative movement between said wipers and said plates, and spring pressed plungers for maintaining the acting edges of the plates normally flush with the acting edges of the wipers.

9. In a lasting machine, the combination with toe wipers and operating means for advancing and closing the wipers to lay an upper over an innersole; of metallic toe embracing plates secured to the under side of said wipers and movable relatively thereto, means for heating said plates, and means to limit the relative movement of the wipers and the plates and cause the plates to control the distance which the wipers may be advanced over the shoe bottom.

10. In a lasting machine, the combination with end wipers and operating means for advancing and closing the wipers to lay an upper over an innersole; of metallic end 5 embracing plates located under said wipers and having a relatively wide acting face of a similar contour to that of the wipers, means connecting said plates and said wipers, said connecting means permitting 10 relative movement between the wipers and the plates, and means for heating said metallic toe embracing plates.

11. In a lasting machine, the combination with end embracing wipers adapted for advancing and closing movement to lay an upper over an innersole, of metallic end embracing plates located under said wipers and having an acting face wide enough to extend 15 down across the innersole and press the upper against the side face of the last while 20

the wipers advance and close over the shoe bottom, and yielding means against the resistance of which relative movement of the wipers and said plates can take place for said overwiping operation.

25

12. In a machine of the class described, end lasting mechanism comprising two sets of toe embracing plates having similarly shaped acting edges formed and arranged to embrace the toe of a shoe, a single operating means for advancing and closing both sets of said plates, and a connection between 30 said plates for causing the lower set of plates to clamp the upper yieldingly against the side face of the last while advancing 35 and closing the upper set of plates over the shoe bottom.

In testimony whereof I have signed my name to this specification.

MATTHIAS BROCK.
